(57) CLAIM

An ornamental design for a meditation bench, as shown and designed.

DESCRIPTION

FIG. 1 is a top plan view of a meditation bench showing my new design;

FIG. 2 is a front elevational view thereof with legs in an open position;

FIG. 3 is a rear elevational view thereof with legs in an open position;

FIG. 4 is a right end elevational view thereof;

FIG. 5 is a left end elevational view thereof;

FIG. 6 is a plan bottom plan view in a closed position thereof;

FIG. 7 is a plan bottom plan view in an open position thereof;

FIG. 8 is a perspective view thereof with the meditation bench lying on the front side in the open position; and,

FIG. 9 is a top view in an open position thereof.

The broken lines in FIGS. 1-9 depict a feature of the meditation bench included for the purpose of illustrating an attachment configuration that does not form a part of the claimed design.

1 Claim, 9 Drawing Sheets
